Primary Examiner—James R. LargenAttorney, Agent, or Firm—Pravel, Gambrell, Hewitt, Kimball & Krieger*[57] CLAIM

The ornamental design for a infant's bathing support, as shown and described.

DESCRIPTION

FIG. 1 is a front perspective view of an infant's bathing support showing my new design;

FIG. 2 is a front elevational view thereof;

FIG. 3 is a right side elevational view thereof, the left side being a mirror image of the right side;

FIG. 4 is a top plan view thereof;

FIG. 5 is a rear elevational view thereof; and,

FIG. 6 is a bottom plan view thereof.

FIG. 1

FIG. 2FIG. 3*FIG. 5*FIG. 4*FIG. 6
